UNITED STATES PATENT OFFICE

2,441,917

AUXILIARY CHAFFER FOR THRESHING MACHINES

Amedee Dion, Ste. Therese de Blainville,
Quebec, Canada

Application August 30, 1945, Serial No. 613,616

2 Claims. (Cl. 130—24)

1

The present invention pertains to a novel chaffing device to be used as an auxiliary chaffer on a threshing machine. The usual chaffer embodied in such a machine is disclosed, for example, in Canadian Patent No. 217,573, of April 11, 1922, and is disposed at the rear of the machine. Frequently, this chaffer is of insufficient capacity, and an auxiliary chaffer is desirable. The present invention provides such an auxiliary chaffer attached to and extending rearwardly from the usual chaffer.

In order to mount the auxiliary chaffer, a heavy frame member is secured across the rear end of the usual chaffer, and a similar member is hinged thereto on a horizontal axis transverse of the machine. The auxiliary chaffer consists of a series of rearwardly extending notched bars secured to the hinged transverse member, with transverse plates mounted in transversely aligned notches of adjacent bars and covering one face thereof. The uncovered face permits grain to fall through the chaffer while the chaff is drawn upward.

The invention further includes an air breaker or baffle extending downwardly from the forward end of the auxiliary chaffer and dividing the air stream into two parts associated respectively with the usual and the auxiliary chaffers. Also included in the invention is a means for adjusting the angle of elevation of the auxiliary chaffer by means of a supporting crank rotated by a lever which in turn may be locked in selected position in a notched arcuate flange.

The invention is fully disclosed by way of example in the following description and in the accompanying drawings in which:

Figure 1 is a longitudinal section of the attachment applied to the rear end of a chaffer, and

Figure 2 is a plan view thereof.

Reference to these views will now be made by use of like characters which are employed to designate corresponding parts throughout.

In Figure 1 are shown two longitudinal frame members 1 of the chaffer of a threshing machine. The chaffer is shown in detail in Canadian Patent No. 217,573 of April 11, 1922, and consists essentially of a screen comprising spaced angular slats 2 permitting the grain to fall therethrough. The frame members 1 are extended rearwardly beyond the chaffer and carry a transverse member 3 secured beneath and directly rearward of the chaffer by suitable fastening members 4. Directly rearward of the member 3 is a similar transverse member 5 attached to the member 3

by hinges 6 permitting the member 6 to be swung upwardly as will presently appear.

A number of rearwardly extending bars 7 are secured to the member 5 by suitable means such as bolts 8. The upper edge of each bar is serrated or formed with V-notches 9. A plate 10 is laid in each series of transversely aligned notches in the several bars and engages one face of each notch, the other face leaving an opening through which the grain is adapted to fall.

Across the forward ends of the bars 7, at the bottom thereof, is secured an L-shaped plate 11 which also is held by the bolts 8. The downwardly extending portion of the plate provides 15 an air breaker or baffle forming individual air currents at the chaffer 2 and the auxiliary chaffer formed by the bar 7 and the plates 10.

To the ends of the frame members 1 are fastened downwardly extending brackets 12 in which 20 is pivotally mounted a rearwardly extending U-shaped crank 13 engaging beneath the bars 7. At the outer side of one of the brackets 12, the crank is extended also rearwardly in the form of a lever 14 adapted for selective reception in the 25 notches of an arcuate notched flange 15 formed on the bracket 12. The resiliency of the metal from which the parts 13, 14 are constructed permits the lever 14 to be moved out of and into engagement with the notches of the member 15.

30 In various operations of the device it is desirable to regulate the angle of the bars 7 about the axis of the hinges 6. Such adjustment is secured by releasing the lever 14 from the notched member 15 and rotating it about the pivotal mounting of the crank 13, whereupon the elevation of the crank is adjusted to determine the position of the bars 7 resting thereon.

Although a specific embodiment of the invention has been illustrated and described it will 40 be understood that various alterations in the details of construction may be made without departing from the scope of the invention as indicated by the appended claims.

What I claim as my invention is:

- 45 1. A chaffing device comprising a pair of frame members hinged together on a horizontal axis, a plurality of bars extending laterally from one of said members, said bars being formed with aligned V-notches in their upper surfaces, plates secured 50 across said aligned notches to cover one side of each notch, a baffle extending downwardly from said bars at the end nearer said hinge axis, and means for adjusting the angle of said bars about said hinge axis.
- 55 2. In combination with a frame structure and

a chaffer carried thereby, an auxiliary chaffer comprising a member hinged to the rear end of the first chaffer on a horizontal axis transverse of said structure, a plurality of bars extending rearwardly from said member, said bars being formed with alined V-notches in their upper surfaces, plates secured across said alined notches to cover one side of each notch, a downwardly extending baffle provided on said auxiliary chaffer near the hinged end thereof and at an operative distance below said plates, and means for adjusting the angle of said bars about said hinge axis.

AMEDEE DION.
